UNITED STATES PATENT OFFICE.

DANIEL HENNEQUIN AND EDOUARD PLAGNES, OF PARIS, FRANCE.

PROCESS OF MAKING READY FOR PRINTING FROM BLOCKS AND FORMS.

No. 911,497.

Specification of Letters Patent.

Patented Feb. 2, 1909.

Application filed March 21, 1908. Serial No. 422,425.

To all whom it may concern:

Be it known that we, DANIEL HENNEQUIN and EDOUARD PLAGNES, citizens of the French Republic, and residing at 139th Rue 5 de Vaugirard, Paris, France, have invented certain new and useful Improvements in the Processes of Making Ready for Printing from Blocks and Forms, of which the following is a specification.

As is well known a great loss of time is occasioned in making ready for printing from blocks and forms, by reason of the inequalities which are present in the surface of the different blocks in one and the same form. Heretofore these inequalities have usually been removed by arranging underlays either under the metal of the block or overlays on the platen or impression cylinder. This work requires great skill, scrupulous care, is very tedious and does not always give satisfaction because the edges of these underlays or overlays form inequalities relatively to the adjacent edges that have an injurious effect on the uniformity of the printing.

Now the improved process which forms the subject of this invention has for object to avoid this loss of time while providing an automatic register of the counterparts and 30 an absolutely uniform pressure over all parts of the block of one and the same form.

The improved process consists in coating the platen or impression cylinder with a layer of material capable of taking an exact 35 impression of all the inequalities of the surface of the blocks. This impressed layer which constitutes the counterpart of the blocks of which it follows the concavities and convexities exactly remains in place on 40 the platen or impression cylinder during printing. The sheet to be printed is placed between this impressed layer and the form, and it thus receives uniform pressure and as it bears uniformly on all points of the said 45 form, the impression resulting therefrom will have absolute sharpness both in the semitones as well as in the lights and the solids. The material which constitutes this impressed layer must be such that it will 50 adhere to the platen or impression cylinder during the taking of the impression of the form, and also set with rapidity to an extent sufficient to withstand the pressure of the printing process without varying in thickness in its various parts. Moreover, this 55 impressed layer must not clog or adhere to

the block. This double result is obtained by the process described hereinafter and of which the accompanying diagrammatic drawing shows the different stages of the 60 method of working in which:

Figure 1 shows a form of printing machine and a cylinder as seen before putting in the form. Figs. 2, 3 and 4 show these same parts during the successive stages of 65 putting in the form.

It is assumed that the form, *a*, is composed of removable type process blocks and line engraving blocks. The blocks having been brought to type height at their respective 70 places in the form in the usual manner, a proof is then taken from which the margins outside the blocks are removed. The platen or impression cylinder, *b*, is then clothed with stretched sheets the last of which is intended to take the impression. By means of a hand roller the blocks are coated with a composition *c* (Fig. 2) capable of causing each proof *d* above mentioned to adhere momentarily to its respective block. This first composition is such that it will fix the proof 75 very lightly upon its block while affording suppleness to the impression which will be made subsequently. This composition is composed per 1,000 grams of about 600 grams of powdered white lead and 300 grams of vaseline well worked up together 80 with the addition of 100 grams sulfuric ether. The proofs having been thus fixed upon their respective blocks they are coated 85 (Fig. 3) by means of a brush with a certain thickness of another composition *c* consisting per 1,000 grams of about 270 grams of asphaltum and 360 grams of powdered white lead mixed together and dissolved in 320 90 grams of benzine. This mixture is well worked up together and sifted and to it are added 50 grams of ether. This second composition *c* sets after drying for a few seconds, and, as soon as it has become sufficiently 95 resistant to the touch, it is passed through the printing machine without ink and without a sheet. The result of this operation is that the proofs *d* become detached from the blocks and adhere strongly 100 to the clothing of the platen or cylinder in their correct places (Fig. 4). The blocks *a* are then cleaned for the purpose of removing the first composition and the splashings 105 of the second composition. By means of these various operations there are obtained 110 exact impressions of very great delicacy both

of the blocks as well as of the place occupied by each counterpart on the platen or impression cylinder. Immediately afterwards a sheet *g* which has been previously moistened is pasted on the platen or impression cylinder *c* and a proof is taken. The weak parts which may exist in the engravings are strengthened by applying over the proof *g* thus obtained a few coats of the asphaltum composition in greater or lesser thickness, according to the degree of intensity of the faults, and another sheet, *h*, is pasted on as before (Fig. 4). Then an impression is taken in the machine for the purpose of distributing uniformly the excess composition. This distribution is always effected uniformly so that there need be no hesitation in coating again rapidly to some extent the parts adjacent to those which are considered as being weak. If this is necessary the operation is repeated until a perfect result is obtained. When the proof is considered to be a good one, the make-ready is complete and the printing is proceeded with in the usual way.

From the foregoing, it will be seen that a print thus obtained has equalized in a perfect manner the pressure over all points of the block so that the sheet to be printed is obliged by this counterpart to take all the ink placed on the metal. The pressure is so well regulated that the faults of the wooden foundation cannot be felt unless it contains cavities of an extent which are never encountered in practice. The impressed layer being composed of a material which is both supple and firm, offers less resistance than the metal, and therefore cannot crush in the latter at the place where there may be cavities in the wood. Further, as the sheet takes the ink at all parts of the block by reason of the uniform pressure thus produced, there is no necessity for applying too much ink as is often done with a defective make ready and consequently the lights in the engravings will remain very clear and the solids will be sufficiently intense. By suitably regulating the inking, spotting will always be avoided, and it will not be necessary to insert fly leaves in cases where strong engravings are printed which require a very copious supply of ink.

The ingredients of the two compositions employed in this process may obviously vary,

the essential feature being that these compositions shall be adapted to the end in view. Thus for example the first composition may be composed of any product having a mineral basis other than white lead. The same applies to the composition in which the mixture of asphaltum and white lead may be replaced by any other mixture which is soluble in an ether and gives an instantaneous drying material.

The term "cut out proof sheets" used throughout the claims is used to define the proof sheets which are trimmed or have their margins removed outside of the blocks as set forth in the first paragraph of page 3.

Having thus described our invention, what we claim as new and desire to secure by Letters Patent is:—

1. The herein described improved process of making an overlay for a printing form containing engraved blocks, which consists in coating the blocks with an adhesive composition having a mineral basis, placing cut-out proof sheets on said blocks, applying pressure to cause a momentary adherence of said proof sheets to said blocks, and coating the back of said proofs with an adhesive quick drying plastic composition derived from a solution of material in ether, forming in same an exact counterpart of the concavities and convexities of the blocks and removing said counterpart from the blocks.

2. The herein described improved process of making an overlay for a printing form containing engraved blocks, which consists in coating the blocks with an adhesive solution of white lead, applying cut-out proofs to the coated surface of said blocks, coating the backs of said proofs with a plastic composition of asphaltum and white lead dissolved in an ether and passing said blocks with said coated proofs thereon through the machine whereby the said coated proofs are transferred from the blocks and caused to adhere to the clothing of the impression element of the printing machine.

In testimony whereof we have hereunto set our hands in presence of two subscribing witnesses,

DANIEL HENNEQUIN.
EDOUARD PLAGNES.
